DOOR CHIME OR SIMILAR ARTICLE

Norman William Stevenson, Macclesfield, England, assignor to V. & E. Friedland Limited, Macclesfield, England, a British company

Filed Dec. 9, 1964, Ser. No. 82,970

Claims priority, application Great Britain June 9, 1964

Term of patent 14 years

(Cl. D72—1)

FIG-1.

FIG-4.

FIG-2.

FIG-5.

FIG-3.

FIG-6

FIGURE 1 is a front elevational view of a door chime or similar article showing my new design.

FIGURE 2 is a plan view of the chime of FIGURE 1.

FIGURE 3 is a side elevational view of the chime of FIGURE 1.

FIGURE 4 is a rear elevational view of the chime of FIGURE 1.

FIGURE 5 is a front perspective view from above and to one side of one embodiment of the chime of FIGURE 1.

FIGURE 6 is a section on line 6—6 of FIGURE 5 of the front casing portion of the chime of FIGURE 1.

FIGURE 7 is a front perspective view from above and to one side of a second embodiment of the chime of FIGURE 1.

FIGURE 8 is a section on the line 8—8 of FIGURE 7 of the front casing portion of the chime of FIGURE 1.

FIGURE 9 is a front perspective view from above and to one side of a third embodiment of the chime of FIGURE 1, and

FIGURE 10 is a section on line 10—10 of FIGURE 9 of the front casing portion of the chime of FIGURE 1.

I claim:

The ornamental design for a door chime or similar article, substantially as shown.
